JAMES LOCKE STRICKLAND, OF WESTPORT, NOVA SCOTIA, CANADA, ASSIGNOR TO
HARRY RICHARDS MCLELLAN, OF ST. JOHN, CANADA.

ROTARY INTERNAL-COMBUSTION ENGINE.

1,019,856.

Specification of Letters Patent. Patented Mar. 12, 1912.

Application filed October 19, 1908, Serial No. 458,479. Renewed November 15, 1911. Serial No. 660,470.

To all whom it may concern:

Be it known that I, JAMES LOCKE STRICKLAND, of Westport, in the Province of Nova Scotia, Canada, have invented certain new and useful Improvements in Rotary Internal-Combustion Engines, of which the following is a specification.

My invention relates to improvements in rotary internal combustion engines, and the objects of my invention are to provide simple and effective means for introducing and regulating the flow of the explosive mixture and to simplify and improve the construction of the machine generally, as described hereinafter in detail in the accompanying specifications and drawings.

In the drawings, Figure 1 is a vertical longitudinal section through the engine. Fig. 2 is a side view of the same. Fig. 3 is a section on the line 2—2, Fig. 1. Fig. 4 is a transverse section through the valve member taken on substantially the line 3—3, Fig. 2. Fig. 5 is a perspective view of the valve member. Fig. 6 is a cross section of the cylinder on the line 4—4, Fig. 1. Fig. 7 is a sectional view on the line 5—5, Fig. 4.

In the drawings, like letters of reference indicate corresponding parts in each figure.

Referring to the drawings, A represents a base of suitable form with standards 10 and 11 thereon, having bearing boxes 12 and 13 at the top thereof. The bearing box 13 journals the main rotating shaft B, to the inner end of which the rotating frame C is secured. This frame is formed with a plurality of radial arms 14 having bearings 15 at their extremities, which journal the trunnions 16 on one side, to a plurality of cylinders D, there being four cylinders in the embodiment illustrated.

The trunnions 17 on the opposite side of the cylinders are journaled in bearings 18 formed on the extremities of the arms 19, of a spider E, which is rotatably mounted on the fixed shaft F supported from the bearing 12 and having a crank pin 20 formed on its inner extremity. This crank pin is engaged by the bifurcated ends 21 on the piston rods 22, the ends fitting one within the other, and the outermost end having a sleeve 23 attached thereto, which is mounted on the crank 20, the ends of the other piston rods having engagement with the outer surface of the sleeve 23. By these means, a much better fit can be obtained as the sleeve

23 only engages the crank pin and the remaining bifurcated ends on the piston rod have only a slight oscillatory movement on the sleeve.

The pistons 24 on the ends of the piston rods are of the usual form, suitable packing boxes 25 being provided on the inner ends of the cylinders, and small vent cocks 26 on the outer end.

The explosive fluid which may be gasoline vaporized by a suitable carburetor, is introduced through the pipe 27, the end of said pipe extending into a conduit 28 in a valve member G. This valve member is loosely mounted on the shaft B, and is provided with a conduit 28 which leads to the face of an adjustable disk 29, the said disk being held in position by an annular flange 30 on the valve member and being brought to and held in either of two adjusted positions by a spring locking handle 31 of usual form coöperating with stops 32 and 33. This disk 29 has an elongated, arcuate port 34 therein with which the conduit 28 communicates and against the face of the disk a rotatable member H bears formed with chambers having ports 35 in the face thereof, which communicate with conduits 36 in radial arms 37, the outer extremities of the conduits being placed in communication with the cylinder, as hereinafter described.

The valve member is held against the rotary member by means of a suitable compression spring 38, bearing against the valve member and the bearing box 13.

In order to permit of slight movement between the valve member and the pipe 27 the pipe extends slightly into the conduit 28, and is provided with a washer 39 of leather or other flexible material, which is adapted to be drawn against the opening of the conduit by the suction of the engine.

The extremities of the arms 37 are turned inwardly and extend into the hollow trunnions 16, the said trunnions communicating with passageways 40 cored in the sides of the cylinders, and which lead to the inlet ports 41 in the interior of the cylinders. This inlet port is also connected at a passage-way 42 with a second port 43 slightly beyond the center of the cylinder.

In order to permit a slight outward and inward adjustment of the ends of the arms 37, the said ends extend slightly into the hollow trunnions and the escape of com-

bustible fluid is prevented by packing boxes 44. It is also desirable to provide means for shortening and lengthening the arms 37, slightly, and this may be conveniently accomplished by making the arms telescopic in form and providing a packing box 45 at their joint.

The exhaust of the cylinders is effected through the hollow trunnions 17, which have ports 46 on their top, communicating with conduits 47, which are formed with a U-shaped bend at their outer extremities, and which communicate at their inner extremities with an annular space 48 in a chest I, and this space communicates through apertures 49 with the passage-way 50 provided in the shaft F. The escape of the exhaust products at opposite ends of the chest I is prevented by suitable packing boxes 51 and 52.

The object of forming the connection between the conduit 47 and the trunnion on the outer side, is to enable the centrifugal force to hold the trunnion tightly against the end of the conduit, as the trunnion, during the rotation of the cylinder, oscillates slightly and otherwise, it would be difficult to secure a tight joint between the two.

The ignition of the explosive mixture in the cylinder is effected through suitable sparking plugs 52 of well known construction, and suitably electrically connected to segmental rings 53 and 54 adapted to co-act with brushes 55 and 56 to make the necessary electrical connections, as well known in this type of engine.

In order to vary the moment at which ignition takes place, a handle 57 may be provided for adjusting the position of the brush 56.

In operation the cycle in each cylinder is the same. The valve controlling the inlet port 35 is arranged to open as soon as the piston shall have moved outwardly sufficiently to close the exhaust port and the port 43, the two ports being substantially at the same point, but the exhaust port being a slight distance farther outwardly. The port 35 is then opened and the combustion flows in through the passage way 28, the port 35, conduit 36, passage way 40 and inlet port 41. Before the piston starts to move inwardly the port 35 will have moved past the port 34, cutting off the supply of combustible. The piston then starts to move inwardly and ignition is made to take place. This propels the piston inwardly with great force and as soon as the piston passes the exhaust port, the unconsumed products of combustion flow out and immediately after the exhaust port opens the piston will have passed the port 43 and the mixture of combustible which has been compressed on the rear side of the piston will flow around through the passage way 42 into the outer

side of the cylinder and will gradually fill the same as the exhaust products pass out. The second outward movement of the piston will again close the exhaust port and the port 43 and the combustible will be compressed in the outer end of the cylinder and ignited again.

It may be observed that the movement of the piston outwardly is made sufficiently quickly to prevent any of the combustible flowing out of the exhaust port when both ports 43 and 46 are in communication with each other.

When it is desired to reverse the engine, the plate 29 is turned to about one eighth of a revolution, and this will cause the port 34 to be disposed in the reversed position with respect to the ports 35 so that the combustible will be allowed to flow in at the proper moment for the reverse operation.

What I claim as my invention is:—

1. In a rotary internal combustion engine and in combination, a fixed crank pin, a plurality of piston rods pivoted thereon having pistons on their extremities, substantially radially disposed cylinders inclosing the pistons and being formed with a trunnion on each side, one of said trunnions on each cylinder being formed with an exhaust port opening through the trunnion toward the outer end of the cylinder, a rotatable element having bearings thereon adapted to journal those trunnions on the cylinders in which the exhaust ports are formed, said bearings having ports therethrough on the outer side adapted to register with the ports in the trunnions, whereby the centrifugal force will tend to hold the trunnions in tight contact on their outer side with the bearings, exhaust conduits in communication with the ports through the bearings, means for rotatably supporting the opposite side of each cylinder to that which said rotatable member supports, and means for supplying the cylinders with explosive fluid and igniting the same at the proper moment.

2. In a rotary internal combustion engine, the combination with the rotating cylinders and combustible supply pipes connected thereto, of a rotatable member having a plurality of compartments therein, each being placed in communication with one of the supply pipes and being provided with a suitable port in the side, a valve member spring held against the rotatable member having an elongated outlet port adapted to register with the ports in the compartments and having a suitable inlet port on the opposite side, and a supply pipe extending into the inlet port and having a flexible washer 39 thereon adjacent to the port.

3. In a rotary internal combustion engine, the combination with the rotating cylinders and combustible supply pipes connected thereto, of a rotatable member having a plu-

rality of compartments therein, each being placed in communication with one of the supply pipes and being provided with a suitable port in the side, a valve member spring held against the rotatable member and formed on the face with an adjustable disk 29 having an arcuate port therein adapted to register, during certain parts of the revolution, with the ports in the compartments, and means for supplying the valve member with combustible fluid.

4. In a rotary internal combustion engine, and in combination, a plurality of rotatable cylinders, combustible supply pipes communicating with the cylinders and having tele-

scopic packed joints intermediate of their lengths, a rotatable member formed with a plurality of chambers, with which the inner ends of the supply pipes communicate, the said chambers being each formed with an ²⁰ inlet port, and a combustible supply member having an elongated port therein adapted to communicate with the ports in the chambers, during certain parts of their revolution.

In witness whereof I have hereunto set 25 my hand in the presence of two witnesses.

JAMES LOCKE STRICKLAND.
